UNITED STATES PATENT OFFICE

1,997,885

CHAIN POST BINDER AND GUIDE PLUG
THEREFORGeorge W. Newman, St. Louis, Mo., assignor to
Loose Leaf Metals Company, a corporation of
Missouri

Application March 30, 1934, Serial No. 718,110

3 Claims. (Cl. 129—41)

The invention relates to chain post binders in which the sheet-engaging posts are in the form of connected links. These chain sections are housed within the chamber of the lower binder bar and project through openings in the upper wall thereof, their outer ends being attached to the upper binder bar and controlling mechanism being provided for forcing them outwardly and withdrawing them in order to bind the bars securely upon the sheets attached to the posts.

Difficulty has been encountered in providing suitable guiding means for changing the direction of the posts as they emerge from or are withdrawn into the housing.

This invention consists of a plug adapted to fit within the post outlets and be securely anchored within the binder bar, and having a guide channel for the chain opening through its upper end and through a side wall.

In the accompanying drawing:

Fig. 1 is a detail perspective view of a chain post binder, partly open;

Fig. 2 is a view in perspective of the improved guide plug;

Fig. 3 is a plan section of the lower binder bar; and

Fig. 4 is a detail central longitudinal section thereof.

There is shown in the drawing a chain post binder comprising upper and lower binder bars 10, 11, both of the usual form, being made of sheet metal folded to flattened tubular shape,—the upper bar being provided with through apertures to receive the posts and the lower one constituting a housing for the chain posts 12, 13, and the actuating mechanism therefor, and having outlets for the outer ends of the posts.

The post controlling mechanism, with the details of which, however, this invention is not concerned, is shown as comprising a pair of slotted bars 14, 15, to which the chains 12, 13, are attached and which are provided with threaded apertures for receiving an actuating screw rod 16.

The upper wall of the bar 11 is apertured, as shown at 17, 18, to provide outlets for the chain posts, and these apertures are made sufficiently large to receive the improved guide plugs 19. The plug 19 fits snugly within one of the apertures 17, 18, and is provided with an annular flange 20 at its upper end which seats against the outer face of the top wall of the bar 11, the length of the plug being such that it seats against the inner surface of the lower wall of the bar. The plug is provided at its inner end with an axially

projecting boss 21, for entering a suitable aperture in the lower wall of the bar, this aperture having flaring walls.

The plug being inserted through the aperture 17, its boss 21 is upset or swaged to completely fill the aperture in the lower wall of the bar, as indicated in Fig. 4, thereby firmly anchoring the plug within the bar and drawing its flange 20 snugly against the upper wall thereof.

The plug 19 is provided with an elbow channel 22, which opens through its upper end and through its side wall, this channel being of such size that the chain post may pass therethrough, the links of which the post is formed being sufficiently short to make the channel turn. In locating the plugs within the binder bar it is, of course, necessary to have the lateral opening of the channel directed longitudinally of the bar.

The invention, therefore, provides a simple and efficient chain guide in the form of a plug, which may be securely anchored in place and contributes to the rigidity of the binder bar. The invention cheapens the cost of manufacture, and, in addition to providing a reliable guide for the flexible post, strengthens the binder bar and permits the use of lighter gauge sheet metal in its manufacture.

I claim as my invention—

1. A guide plug for chain post binders having an elbow channel opening through an end and side wall and having an annular flange surrounding the apertured end, and an axially projecting boss at its opposite end.

2. In a loose leaf binder, the combination with a chambered binder bar equipped with chain post mechanism and having outlets in one wall for the posts and flaring apertures in its opposite wall, of guide plugs occupying such openings and each having an elbow channel opening through its outer end and through its side wall within the bar chamber, each of such plugs having an annular flange at its upper end for engaging the upper face of the bar and an axial boss at its inner end to enter and be expanded within one of the flaring apertures.

3. In a loose leaf binder, the combination with a chambered binder bar equipped with chain post mechanism, and having outlets for the posts and apertures opposite such outlets, of a guide plug occupying and overlapping the margins of each pair of the named openings and having an elbow channel for a chain post.

GEORGE W. NEWMAN.
